JOSEPH DOMBER AND MORRIS DOMBER, OF BRONX, NEW YORK, N. Y., ASSIGNEES TO
PEERLESS SAMPLE CARD CO. INC., OF NEW YORK, N. Y., A CORPORATION OF NEW
YORK

SAMPLE CARD

Application filed April 18, 1928. Serial No. 271,078.

This invention relates to improvements in sample cards and more especially to sample cards used for mounting samples of textile fabrics.

5 A particular object of the invention is the provision of a sample card which can be manufactured with a minimum of waste, which will be light in weight and which will permit the ready insertion and withdrawal 10 of the samples mounted thereon.

Further objects of the invention will be apparent from the specification and drawings in which

Fig. 1 is an elevation of our improved sample card with several samples mounted thereon.

Fig. 2 is a sectional view along the line 2—2 of Fig. 1.

Fig. 3 is a sectional view along the line 20 3—3 of Fig. 1.

Fig. 4 is an enlarged sectional view along the line 4—4 of Fig. 1.

Fig. 5 is a rear elevation of our improved card with a portion of the card torn away 25 to show the manner of construction.

Fig. 6 is a sectional view along the line 6—6 of Fig. 5.

Fig. 7 is an elevation showing a modification of the first form of sample holder ill- 30 lustrated.

Fig. 8 is an elevation showing the manner in which two of our improved sample cards are joined together.

Fig. 9 is a sectional view of the two cards 35 shown in Fig. 8.

Fig. 10 is a perspective view of a book showing the assembly of a number of our improved sample cards.

Fig. 11 is a sectional view showing the assembly of our improved cards in a cover.

A represents the body of the sample card in which are cut the slots B, in which the individual sample holder or mount C is inserted.

45 Heretofore it has been the custom in the manufacture of sample cards used for displaying textile samples to use a large sheet for the body of the sample card, to make the necessary number of slots in the body of the card for the insertion of the individual

sample holders, and to reinforce this body with a sheet of exactly the same size on the back thereof, so that this rear sheet acted as a holder and support for said individual sample mounts.

55 We have improved this known construction by using a single sheet of paper A as the base of our sample card and we make the reinforcement for holding the ends of the individual sample mounts by turning over each vertical edge of the sample card to form a pocket A' as is more clearly shown in Figs. 5 and 6 of the drawing.

60 This, of course, necessitates the use of a larger sheet for the body of the sample card, as the material for the back pockets forms part of the front sheet.

65 The vertical edge on each side is turned over, however, only sufficiently to cover the 70 slots on the face of the card as is clearly shown in Figs. 5 and 6, it being understood that each rear edge is pasted to the front sheet A at a distance sufficiently far from the edge of the sheet A to clear the slots B on 75 each side to form pockets having aligned openings.

Where it is desired to join the individual cards together, this is done by using gum tape or cloth C' for the purpose, this gum tape or 80 cloth being flexible so that the sheets may be joined to each other in a continuous row as is shown in Figs. 8, 10 and 11.

In Fig. 1, we have shown the pockets A' provided with straight slots B in which the 85 ends of the holder C fit.

In Fig. 7, we have shown a modified form of opening to receive the sample holder C. This permits marking of a notation or memorandum on the end of the holder C, which 90 notation or memorandum is exposed at all times, whereas in the form of slot shown in Fig. 1, the end of the holder is covered by the body of the card.

95 It should be understood that we are not limited to constructing our new form of sample card by turning the edge of the card rearwardly, as the same economy in construction may be effected by turning the edge of the card forwardly and pasting the edge to the 100

body of the card at a short distance from the line of fold.

In this case, the slots to hold the individual sample holders would, of course, be cut in the 5 portion of the card which is turned over.

The same result could be secured by taking two narrow rectangular strips of paper having slots formed therein, and pasting said narrow strips at their edges to a large sheet of 10 paper.

The same result may also be secured by taking a rectangular base sheet, cutting a series of slots near each vertical edge of the base sheet and then pasting on the back near each 15 edge a narrow strip of paper to form pockets or supports for the individual sample holder.

Having fully described our invention, what we claim is:—

A sample card device comprising a mount 20 having aligned slots adjacent its edges, said mount having its edges rearwardly and inwardly turned to provide end pockets, the inwardly turned edge portions being connected to the rear surface of said mount intermediate 25 said slots, supplemental cards having pieces of textile fabric connected thereto, said supplemental cards being located upon the front surface of said mount and having their edges extending through said slots into said pockets, 30 said mount being free of any other means for holding said supplemental cards in position.

In testimony whereof we affix our signatures.
